to The Weatherhead Company, Cleveland, Ohio,
a corporation of Ohio

Application March 8, 1949, Serial No. 1,263

Term of patent 14 years

(Cl. D91—3)

To all whom it may concern:

Be it known that I, John E. Szitar, a citizen of the United States, residing at Cleveland Heights, Ohio, in the county of Cuyahoga and State of Ohio, have invented a new, original, and ornamental Design for a Drain Cock or Similar Article, of which the following is a specification, reference being made to the accompanying drawing, forming a part thereof.

In the drawing:

Fig. 1 is a side elevation of a drain cock or similar article, showing my new design;

Fig. 2 is a top plan view of the drain cock; and,

Fig. 3 is an end elevation thereof.

I claim:

The ornamental design for a drain cock or similar article, as shown.

JOHN E. SZITAR.
